UNITED STATES PATENT OFFICE.

RODERICK MACRAE, OF BALTIMORE, MARYLAND, ASSIGNOR TO THE
DONALDSON-MACRAE ELECTRIC COMPANY, OF SAME PLACE.

AUTOMATIC SWITCH FOR ELECTRIC MOTORS.

SPECIFICATION forming part of Letters Patent No. 453,287, dated June 2, 1891.

Application filed August 27, 1890. Serial No. 363,213. (No model.)

To all whom it may concern:

Be it known that I, RODERICK MACRAE, a citizen of the United States, residing at Baltimore, in the State of Maryland, have invented
5 certain new and useful Improvements in Automatic Switches for Electric Motors, of which the following is a specification, reference being had therein to the accompanying drawing.

10 This invention relates to certain new and useful improvements in automatic switches for use upon electric motors; and it has for its object, among others, to provide a simple and cheap automatic switch for use on small
15 constant-current motors to prevent the armature from attaining too high a speed and injuring itself in case the belt breaks or the load is thrown off. The parts are so arranged that when a certain predetermined speed is
20 attained the toggles close up and strike a lever which releases the switch which short-circuits the two poles of the motor.

Other objects and advantages of the invention will hereinafter appear, and the novel
25 features thereof will be particularly pointed out in the appended claims.

30 The invention is clearly illustrated in the accompanying drawing, which, with the letters of reference marked thereon, forms a part of this specification, and in which I have shown in side elevation such parts as constitute or co-operate with my improvement.

35 Referring now to the details of the drawing by letter, A designates an armature of known construction; B, its shaft, supported in a suitable bearing C at the front, which bearing is carried by a fixed portion D or arm of the motor.

40 E are toggle-levers pivotally connected together, as shown, and at their inner ends pivotally connected with the sliding boxes or bearings a, which are free to slide on the armature-shaft between the bearing C and a nut or other similar provision b on the end of the said shaft. A coil-spring F surrounds the
45 shaft between the two bearings a and serves to normally keep the said bearings separated at their maximum distance from each other, but which is compressed under abnormal condition.

50 Affixed to the part or arm D is an arm G,

the upper portion of which extends horizontally and its inner end is curved downwardly and outwardly, as shown. It is secured to the arm D in any suitable manner—as, for instance, by a screw or bolt d.

Depending from the arm G, near its outer end, is a block H, of insulating material, secured thereto in any suitable manner—as, for instance, by screw e—and to said block are affixed the metallic contact-points I, which are connected by wire f with the poles or binding-posts g h of the motor, which are secured to a base-board J.

Pivoted to the outer end of the curved portion e of the arm G by suitable means, as the pivot i, is a lever K, the free end of which is connected with the outer end of the horizontal portion of the arm G by a spring L, connected with the two parts in any suitable manner. This lever K carries a contact-point j so arranged relatively to the contact-points I that when said lever is released and is pulled upward by the spring L the said contact-point will engage the points I and short-circuit the two poles of the motor.

M is a lever pivoted near its center, as at k, to the outer end of the horizontal portion of the arm G, with a vertical portion arranged to normally rest upon the upper face of the free end of the lever K and hold the same down against the power of the spring L. The upper portion of this lever M is inclined inward, as shown, and is designed to be actuated by the toggles as they are closed. I preferably provide at the outer portions of the toggles projections, as l, to engage the said inclined arm when the speed exceeds a predetermined amount, although these projections may be sometimes omitted and the inclined portions of the lever M actuated by direct engagement of the toggle-levers.

The operation will be readily understood from the above description when taken in connection with the drawing, and a detailed description thereof is not deemed necessary.

What I claim as new is—

1. The combination, with the armature, its shaft, and the toggle-levers on said shaft, of the fixed contact-points, the spring-actuated lever independent of the armature-shaft and carrying a contact-point, and a holder for said

lever, arranged to be engaged directly by and released by the toggle-levers under abnormal condition, substantially as described.

2. The combination, with the armature and 5 its shaft and the toggle-levers thereon, of the fixed contact-points connected with the poles of the motor, the movable contact-points carried by a spring-actuated lever, and the pivoted lever having one arm arranged to normally keep the spring - actuated lever depressed and its other end arranged in the path of the toggle - levers under abnormal speed, substantially as described.

3. The combination, with the armature and 15 its shaft and the toggle-levers thereon provided with projections *l*, of the fixed contact-points connected with the poles of the motor, the lever carrying the movable contact-points, and the pivoted lever arranged to engage said 20 lever and to be actuated by the projections on the toggle-lever, as set forth.

4. The combination, with the armature, its shaft, the toggle-levers thereon, and the fixed arm *G*, curved at one end, of the lever *K*, pivoted to said curved end and carrying contact-points, the spring *L*, connecting the free end of the lever *K* with the arm *G*, the fixed contact-point carried by an insulated block on the arm *G*, and the lever *M*, pivoted to the arm *G*, with a vertical portion engaging the 25 upper face of the free end of the lever *K* and its upper portion inclined to be engaged by the toggles under abnormal condition, substantially as described.

In testimony whereof I affix my signature in 35 presence of two witnesses.

RODERICK MACRAE.
